POWDER EXPULSION MEANS

Joseph E. Kucher, Lyndhurst, N. J., assignor to
 C-O-Two Fire Equipment Company, Newark,
 N. J., a corporation of Delaware

Application October 3, 1947, Serial No. 777,664

9 Claims. (Cl. 169—6)

1

The present invention relates to discharging means for fluids, and more particularly to a discharge head for a container of fluid which is to be expelled by pressure applied thereto.

In fire extinguishing installations such as airplane systems, fire extinguishing fluids are often used in which the vapor pressure of the fluid is so low that the fluid is not self-expelling from its container, or if self-expelling, the rate of discharge is insufficient for efficient fire extinguishing purposes. Further, the vapor pressures of the fire extinguishing fluids vary to a considerable extent over the temperature range in which they are used. In fire extinguishing systems which use fluids as water, methyl bromide, monochlorobromomethane and other fluids of low vapor pressure, the effectiveness of the system depends to a large extent upon quickly delivering the extinguishing agent to the fire by the use of a high rate of discharge. In such systems, it is advisable to use an expelling agent to forcefully expel the fluid from its container.

Airplane fire extinguishing systems are particularly subject to a considerable variation in temperature, particularly when the planes are operated at a high altitude. The low temperature of the high altitude reduces the normal vapor pressure of the extinguishing fluid. Heretofore, in such systems, nitrogen or other gases of high vapor pressure often have been used as the expelling agent. Inasmuch as such gases must be stored in heavy high pressure containers, the weight of the container has presented a difficulty because of the weight limitations of aircraft equipment. Another disadvantage in the use of high pressure gases as the expelling agent is that bulky and cumbersome apparatus is required for the recharge of the system after an operation thereof.

The present invention aims to provide a discharge head which overcomes many of the difficulties and disadvantages of prior devices.

It is an object of the present invention to provide a fire extinguisher discharge head in which the pressure of the expelling agent remains practically constant irrespective of the temperature under which it is operated.

Another object of the invention is to provide a fire extinguisher which is small, compact and light in weight and is therefore particularly adapted for installations where size and weight is of importance.

A further object of the invention is to provide a fire extinguisher discharge head which,

2

after operation thereof, may be easily recharged for successive operation.

A further object of the invention is to provide means for controlling the rupturing of a disc sealing a container of fire extinguishing fluid so that a flap will burst out of the body of the disc, providing a wide opening therethrough, the flap itself remaining attached at one side to the body of the disc.

13 Another object of the invention is to provide a fire extinguisher discharge head and the parts therefor which is simple in construction, economical to manufacture, durable in use, and efficient in operation.

15 In accordance with the present invention, the foregoing objects are accomplished by providing a fire extinguisher discharge head in which an expelling agent is provided by the gases resulting from the combustion of a slow-burning powder. The discharge head is used in an extinguisher in which the fire extinguishing agent is stored in a container provided with a novel discharge head having a combustion chamber for the burning of the powder upon the ignition

20 thereof. The gases from the combustion of the powder are conducted to the surface of the fire extinguishing agent to be expelled which is thereby forced through a siphon tube and through the discharge head to a discharge conduit. A further feature of the invention is a support for a

25 frangible sealing disc normally adapted to close off the combustion chamber from the container for the fire extinguishing agent in which the edge of the support is designed, upon the bursting of the disc, to cut a flap from the body of the disc providing a discharge passage but retaining the flap attached to the body of the disc. In order to cut the flap, a sharp edge is provided on a portion of the disc support while the remaining portion of the edge thereof is rounded off so that the flap is not completely severed from the body of the disc.

30 The construction in accordance with the invention is advantageous in that recharging may be accomplished without removing the container for the fire extinguishing fluid from its operating position. The recharge of fire extinguishing fluid may be poured into the container and the powder expulsion charge inserted in the combustion chamber without the necessity of making up high pressure connections as is the case when gas pressure is used.

35 Another advantage is that a fire extinguisher is provided which is shatterproof under gunfire

inasmuch as internal pressure is developed in the container only during the time of discharge after the powder charge has been ignited.

Other objects and advantages of the invention will be apparent from the following description and from the drawings which show, by way of example, an embodiment of the invention.

In the drawings:

Fig. 1 is a perspective view of an airplane equipped with a fire extinguisher system in accordance with the invention. The fire extinguishing system is shown schematically, one of the containers being broken away to show the syphon tube extending to the bottom thereof.

Fig. 2 is an elevational view of a discharge head in accordance with the invention.

Fig. 3 is an enlarged vertical sectional view of a portion of the discharge head shown in Fig. 2.

Fig. 3a is a view of the remaining portion of the discharge head shown in Fig. 3.

Fig. 4 is a cross-sectional view taken along the line 4—4 of Fig. 3.

Fig. 5 is a bottom view of the main valve member of the discharge head.

Fig. 6 is a top view of a partition member closing the combustion chamber of the discharge head.

Fig. 7 is a cross-sectional view taken along the line 7—7 of Fig. 3a.

Fig. 8 is a cross sectional view taken along the line 8—8 of Fig. 3a.

Fig. 9 is an enlarged sectional view of a plug member of the discharge head.

Referring to the drawings, there is shown an airplane 1 equipped with a fire extinguishing system utilizing control means or a discharge head in accordance with the invention. The fire extinguishing system comprises one or more containers 2 positioned in any suitable location in the airplane, a discharge head 4 at the top of the container, a discharge conduit 5 leading to spaces to be protected, and control means 6 preferably located in the pilot's compartment.

The container 2 may be of any suitable type to withstand the pressure used in expelling fire extinguishing fluid therefrom and is shown as being cylindrical in shape with its outlet at the top thereof. The discharge conduit 5 extends from the discharge head 4 to the spaces to be protected, the terminus of the discharge conduit 5 being shown as perforated ring-shaped tubes 7 in the engine nacelles 8 although other distribution means may be employed. Selector valves 9, which may be of the electromagnetic type, are provided to direct the discharge of fluid through the discharge conduit 5 to alternate spaces.

The discharge head 4 comprises a housing or casing 10 having an inlet end 11 adapted to be received in the outlet of the container 2 to serve as a closure therefor, an outlet end 12 adapted to be connected to the discharge conduit 5, and a safety outlet 14 adapted to be connected to a conduit 15 which may lead to the outside of the airplane. An extension 16 on the side of the housing provides housing means for a combustion chamber to be described hereinafter. The discharge head is adapted to be actuated electrically through a control cable 17.

The housing 10 is of generally tubular shape and is formed with a passage 19 extending therethrough having a widened central portion 20. A partition 21 across the widened portion 20 of the passage 19 forms the bottom wall of a valve chamber 22 located at the upper end of the hous-

5

ing. The partition 21 is provided with an aperture 23 forming a fluid passage therethrough, the lower end thereof being threaded to support a syphon tube 24 extending to the lower portion of the container 2. As may be seen in Fig. 3, the axis of the opening of the passage 19 is offset somewhat from the axis of the widened portion 20 so that the syphon tube is supported on one side by the wall of the passage 19. A valve seat 25 is formed in the valve chamber 22 about the aperture 23 by forming a countersunk surface about the aperture. A valve member 26, adapted to engage the valve seat 25, is formed with a seating material 27 positioned on its lower surface and retained in position by a screw 29. The valve member 26 is provided with an apertured flange 30 adapted to guide it as it is reciprocated in an enlarged portion 31 of the upper end of passage 19, and the valve member is resiliently urged against its seat by a spiral spring 32 compressed between the upper surface thereof and a shoulder 33 forming the end wall of the valve chamber 22.

To facilitate assembly of the valve member 26 in the valve chamber 22, the upper portion 12 may be made separately and attached to the housing 10 by threaded engagement therewith as indicated at 33 or by other suitable means. For a like reason the partition 21 may be made separately and positioned in an enlarged end 35 of the widened portion 20 of passage 19, the partition being sealed against fluid leakage by a gasket 36 and retained in position by the upper portion 12. The outlet end 12 of the discharge head is threaded as indicated at 37 for connection with the discharge conduit 5.

A safety plug 38 is adapted to be connected in the safety outlet 14 and is formed with a passage 39 extending therethrough with an enlarged portion of the passage forming a valve chamber 40. An annular valve seat 41 is positioned about the passage 39 within the valve chamber 40. A valve member 42 is placed within the valve chamber 40 and resiliently urged against its valve seat 41 by a spiral spring 44. An outlet end 45 of the safety plug 38 is adapted to be connected to the conduit 15 which may be piped to the outside of the airplane or other space being protected.

The extension 16 of the housing 10 is tubular in shape with a passage extending therethrough providing a combustion chamber 47 and is positioned opposite the safety outlet 14. As shown, the extension 16 is preferably made as a separate member and attached to the main body of the housing 10 by a threaded connection 46 or by other suitable connecting means. The combustion chamber 47 is adapted to receive igniting means 48 at its outer end. A powder charge 49 is adapted to be positioned in the combustion chamber 47. The combustion chamber is closed off from the widened portion 20 of the housing 10 by a partition 51 formed with combustion outlet passages 52 and 54 extending therethrough. The passages 52 and 54 are enlarged at one end thereof and threaded to receive apertured plugs 55 and 56. As may be seen in Fig. 9, the edge of the intersection of the wall of aperture 55a of the plug 55 with its end wall 55b is made sharp over the greater portion of the annular length of the edge as indicated at 55c, while the remaining portion of the annular length of the edge is rounded off as indicated at 55d. The plug 56 is made likewise. Frangible discs 57 and 59 are held in the enlarged portion of the passages 52 and 54 to close the openings thereof by the plugs

55 and 56, fluid tight seals being provided by gaskets 58. One of the discs is adapted to be ruptured by a pressure considerably lower than that required to rupture the other disc. A screening member 60 is positioned in the combustion chamber adjacent the partition 51. The screening member is preferably disc-like in shape and formed with parallel slotted openings 61 providing passage therethrough. A fluid tight seal is provided between the extension 16 and the casing 10 by gaskets 62 and 64. A ceramic heat resisting tube 65 is placed about the siphon tube 24 in line with the discharge from the combustion chamber so that the siphon tube will be protected against damage by the heat of the discharge.

The igniting means 48 may be of any suitable type to ignite the powder charge 49. The igniting means 48 shown in Fig. 3a is comprised of a hollow housing 70 containing a molded insulating material 71 separating electric wires 72 and 73 terminating in an igniting cap 74. The electrical wires 72 and 73 are carried through a cable 75 to the control means 6 and to a source of electric energy.

In the operation of the fire extinguishing system, the control means 6 is actuated to preset one of the selector valves 9 to the open position so that the system is ready to supply fire extinguishing fluid to a selected space. The control means 6 is then further actuated to supply electric energy to the igniting means 48 of the discharge head 4. The powder charge 49 is ignited and rapidly builds up pressure in the combustion chamber 47. The frangible disc 57 is ruptured at a predetermined pressure, the sharp edge 55c of the plug 55 cutting a flap in the frangible disc. However, the rounded portion 55d of the edge of the plug does not complete the severance of the flap and it remains attached to the main body of the disc. The slotted openings 61 of the screening member 60 prevent unburned powder from blocking the passages in the plug 55. The discharge from the combustion chamber 47 then passes through the passages 20 and 19 to the surface of the fluid to be expelled from the container 2. The pressure causes the fluid to flow through the siphon tube 24 and unseat the valve member 26 and thence flow through the discharge conduit 5 to the perforated ring tube 7 where it is discharged. The valve member 26 performs the dual function of preventing the flow of the fluid from the container when the plane is tipped at a large angle as in banking the plane while making a turn and also as a check valve in a multi-container installation in preventing back flow from later discharged containers into containers which have already been discharged. Another function of the valve 26 is to assure the proper operation of the fire extinguishing system in the event one container of a multi-container system has been removed and not replaced, thus leaving the system open at this location.

In the event the pressure rise in the combustion chamber 47 becomes excessive, the frangible disc 57 will also rupture releasing the powder gases to the passage 20. In the event the pressure in passage 20 exceeds a predetermined amount, the safety valve member 42 is unseated thus venting the gas to the atmosphere through the safety outlet conduit 15. As the safety valve 42 is spring-seated, it will return to its seat after the excess pressure has been vented thus maintaining adequate pressure over the fire extinguishing

fluid in the container 2 for the operation of the system.

The recharging of the system may be done by removing the upper portion 12 of the discharge head and refilling the container 2 through the siphon tube 24. The powder charge is replaced by unscrewing the extension 16 of the discharge head so that the powder recharge may be positioned in the combustion chamber 47.

From the foregoing description, it will be seen that the present invention provides a fire extinguishing system discharge head which overcomes many of the difficulties presented by prior discharge heads. In the system in accordance with the invention, the pressure remains practically constant over the range of temperatures under which it is to be operated. The equipment is light in weight and particularly suitable for airplane installations. The system may be easily recharged without the use of auxiliary recharging apparatus. A novel discharge head has been provided which is compact in form and incorporates improved safety release means and a frangible disc support which leaves the flap of the ruptured disc attached to the body thereof so that upon recharging of the system, the rupture disc may be removed in one piece. The apparatus is simple in construction, economical to manufacture, durable in use and efficient in operation.

While the invention has been described and illustrated with reference to a specific embodiment thereof, it will be understood that other embodiments may be resorted to without departing from the invention. For example, the combustion chamber has been described as closed by at least one frangible disc although it is apparent that a valve member adapted to withstand the high temperature such as the valve used in internal combustion engines, might alternatively be used. Further, the discharge outlet has been described as closed by a valve member, while a frangible disc might be substituted for the valve member. Likewise, the container has been described as having one opening thereto, while other constructions might embody a container having a separate opening for the gases from the combustion chamber and a discharge outlet for the fire extinguishing fluid. In still other constructions, the combustion chamber might be formed in a member separate from the discharge head for the container or positioned within the container itself. Therefore, the form of the invention set out above should be considered as illustrative and not as limiting the scope of the following claims.

I claim:

1. A discharge head for a container comprising a casing having a pair of intersecting passages forming a chamber, inlet and outlet ports for the chamber, an apertured partition between the inlet and outlet ports dividing the chamber into a valve chamber adjacent the outlet and a main chamber adjacent the inlet, a valve seat in the valve chamber about the aperture, a valve member in the valve chamber, the casing also forming a combustion chamber, and a second apertured wall between the main chamber and the combustion chamber.

2. A discharge head comprising a housing having a pair of intersecting passages including one fluid passage therethrough, a valve chamber in said passage, a valve member in the valve chamber normally closing the passage and adapted to be opened by predetermined pressure, a second

fluid passage in the housing, a combustion chamber in the housing in fluid communication with the second passage, and a frangible disc normally closing the second passage and adapted to be ruptured by a predetermined pressure.

3. A discharge head housing, the housing having a straight passage extending therethrough, an apertured wall extending across the passage, a valve seat about the aperture, an extension of said housing providing a combustion chamber positioned transversely with respect to the axial length thereof, and a second apertured wall separating the combustion chamber from the passage.

4. A supporting member to provide a backing for a frangible disc, the member having a flat wall with an aperture therein, the edge of the intersection of the flat surface and the opening of the aperture being sharp over a portion of the circumference of the edge and rounded over the remaining portion thereof so that a predetermined pressure of an amount to rupture the disc will sever only the portion of the disc bearing upon the sharp edge, whereby upon the rupture thereof the center of the disc is retained by its edge.

5. A supporting member to provide a backing for a frangible disc, the member having a flat wall with an aperture therein; the edge of the intersection of the flat surface and the opening of the aperture being sharp over the larger portion of the circumference of the edge and rounded over the remaining portion thereof so that a predetermined pressure of an amount to rupture the disc will sever a flap from the main body of the disc leaving an uncut portion of a size sufficient to serve as a hinge for said flap.

6. A discharge head for a container comprising a casing having a vertical passage and a transverse passage intersecting the vertical passage to form a pressure chamber, an apertured partition forming the upper end of the chamber, a valve seat about the aperture in the partition, a valve member adapted to engage the valve seat, the upper end of the vertical passage forming the outlet for the discharge head, an inlet tube adapted to extend through the vertical passage to the apertured partition in fluid communication with the outlet through the aperture in the partition, safety fluid release means at one end of the transverse passage, the transverse passage forming a combustion chamber at its other end, an apertured partition separating the combustion chamber from the pressure chamber, and means providing fluid passage from the pressure chamber to the container.

7. A discharge head for a container comprising a casing having a vertical passage and a transverse passage intersecting the vertical passage to form a pressure chamber, an apertured partition forming the upper end of the chamber, a valve seat about the aperture in the partition, a valve member adapted to engage the valve seat, an inlet tube adapted to extend through the vertical passage to the apertured partition in fluid communication with the aperture in the partition, the transverse passage forming a combustion chamber

ber at its other end, an apertured partition separating the combustion chamber from the pressure chamber, the vertical passage providing a fluid passage between the inlet tube and its wall for the passage of fluid from the pressure chamber to the container.

8. A discharge head for a container comprising a casing having a vertical passage and a transverse passage intersecting the vertical passage to form a pressure chamber, an apertured partition forming the upper end of the chamber, a valve seat about the aperture in the partition, a valve member adapted to engage the valve seat, the upper end of the vertical passage forming the outlet of the discharge head, an inlet tube adapted to extend through the vertical passage to the apertured partition in fluid communication with the outlet through the aperture in the partition, safety fluid release means at one end of the transverse passage, the transverse passage forming a combustion chamber at its other end, an apertured partition separating the combustion chamber from the pressure chamber, means providing fluid passage from the pressure chamber to the container, and frangible means closing the aperture in the combustion chamber partition.

9. A discharge head for a container comprising a body having a pair of vertical and horizontal intersecting passages forming a pressure chamber at their intersection, the upper end of the vertical passage forming the outlet for the discharge head, an apertured partition in the vertical passage above the intersection of the passages, an outlet valve seat about the aperture on the outward side of the partition, an outlet valve member adapted to engage the valve seat, resilient means normally urging the outlet valve member against its seat, an inlet pipe extending outwardly from the lower end of the vertical passage and having an outer diameter smaller than the diameter of the passage to provide a fluid passage therebetween, an apertured partition closing one end of the horizontal passage, a safety valve seat about the aperture on the outer side of the partition, a safety valve adapted to engage its seat, resilient means normally urging the safety valve against its seat, the outer end of the other end of the horizontal passage closed to form a combustion chamber, an apertured partition across the inner end of the horizontal passage to separate the combustion chamber from the pressure chamber; and a frangible disc closing the aperture in the combustion chamber wall.
